UNITED STATES PATENT OFFICE

152,309

DESIGN FOR AN OVER-THE-SHOE BOOT

William T. Williams, Johnson City, N. Y., assignor
to Endicott Johnson Corporation, Endicott,
N. Y., a corporation of New York

Application July 8, 1948, Serial No. 147,443

Term of patent 7 years

(Cl. D7—4)

To all whom it may concern:

Be it known that I, William T. Williams, a citizen of the United States, residing at Johnson City, county of Broome, State of New York, have invented a new, original, and ornamental Design for an Over-the-Shoe Boot, of which the following is a specification, reference being had to the accompanying drawing, forming a part thereof.

In the drawing:

Fig. 1 is a perspective view of an over-the-shoe boot, showing my new design with the top turned up; and

Fig. 2 is a perspective view of the boot with the top turned down in cuff formation.

The essential feature of my design is the split or incision shown in both figures.

I claim:

The ornamental design for an over-the-shoe boot, substantially as shown and described.

WILLIAM T. WILLIAMS.
